Primary Examiner — Mark A Goodwin(74) *Attorney, Agent, or Firm* — The Belles Group, P.C.**CLAIM**

The ornamental design for an air intake cover of an engine, as shown and described.

DESCRIPTION

FIG. 1 is a front-right top perspective view of an air intake cover of an engine showing the new design;
FIG. 2 is a front-left top perspective view thereof;
FIG. 3 is a rear-left top perspective view thereof;
FIG. 4 is a rear-right top perspective view thereof;
FIG. 5 is a front-right bottom perspective view thereof;
FIG. 6 is a front-left bottom perspective view thereof;
FIG. 7 is a rear-left bottom perspective view thereof;
FIG. 8 is a rear-right bottom perspective view thereof;
FIG. 9 is a front plan view thereof;
FIG. 10 is a rear plan view thereof;
FIG. 11 is a right-side plan view thereof;
FIG. 12 is a left-side plan view thereof;
FIG. 13 is a top plan view thereof; and,
FIG. 14 is a bottom plan view thereof.
The broken lines illustrate portion of the air intake cover of an engine that form no part of the claimed design.
